ROOF MOUNTED ENCLOSURE FOR AN AUTOMOTIVE VAN CAMPER

Lorell John Schilling, Galesville, Wis., assignor to
Schilling Industries Inc., a corporation of Wisconsin

Filed Mar. 19, 1969, Ser. No. 16,325

Term of patent 14 years

Int. Cl. D12—14

U.S. Cl. 14—27

Fig. 1

Fig. 2

Fig. 3

FIG. 1 is an elevation of the right side of the enclosure illustrating the design;

FIG. 2 is an elevation of the left side of the enclosure illustrating the design;

FIG. 3 is a front elevation of the enclosure illustrating the design;

FIG. 4 is a top plan view of the enclosure illustrating the design; and

FIG. 5 is a rear elevation of the enclosure illustrating the design.

The van, shown in broken lines, is included for illustrative purposes only.

I claim:

The ornamental design for a roof mounted enclosure for an automotive van camper, as shown and described.
